CLAIM

The ornamental design for an organic matter digester, as shown and described.

DESCRIPTION

FIG. 1 is an isometric view from above.

FIG. 2 is a isometric view from below.

FIG. 3 is a view from above.

FIG. 4 is a view from below.

FIG. 5 is a right side view thereof.

FIG. 6 is a left side view thereof.

FIG. 7 is a front view thereof; and,

FIG. 8 is a rear view thereof.

The broken lines in the figures show portions of the organic matter digester which form no part of the claimed design.
